UNITED STATES PATENT OFFICE.

MAURICE SULLIVAN, OF BROOKLYN, NEW YORK.

VALVE SHIELD.

Application filed December 16, 1925. Serial No. 75,811.

The present invention relates to an improved valve attachment and has particular reference to a housing structure adapted to shield the boiler covering from the escaping steam of a boiler valve.

An important object of the invention is to provide an attachment adapted to be readily mounted in association with boiler valves and the like and intended to 10 confine the activity of the escaping steam so as to prevent injury thereby to the boiler covering.

A further object of the invention is the provision of a shield attachment designed 15 to be readily mounted in association with valves mounted upon boilers and the like and arranged so as to enclose the valve structure and prevent damage from the escaping steam.

20 A still further object of the invention is the provision of a housing adapted to substantially cover the valve structure and having means for the connection of a conducting pipe adapted to conduct the steam escaping from the valve or condensation to a suitable reservoir.

25 A still further object of the invention is the provision of an attachment of the above character designed to be comparatively 30 simple yet durable of construction and which may be conveniently mounted about a valve.

Other objects and advantages of the invention will become apparent as the description progresses.

35 In the accompanying drawings forming a part of this specification and in which like reference characters are employed to designate corresponding parts throughout the same:

40 Figure 1 is a side elevation of the attachment comprising my invention shown associated with a boiler safety valve, showing the portion of a boiler in cross section,

45 Figure 2 is a top plan view of the structure embodying my invention,

Figure 3 is a transverse sectional view taken on the line 3—3 of Figure 1,

Figure 4 is a vertical transverse sectional view taken on the line 4—4 of Figure 2, and

50 Figure 5 is a front elevational view of the assembled structure forming my invention.

In the drawings, wherein for the purpose of illustration is shown the preferred embodiment of my invention, the numeral 10 generally indicates a fragmentary portion of a conventional type of steam boiler, par-

ticularly the type commonly employed in locomotive construction. This boiler is provided with a flanged internally screw threaded opening 11 adapted for connection of a 60 suitable valve such as a safety valve or the like. These boilers are usually covered with a jacket 12 of asbestos or other heat insulating material in order to prevent unnecessary radiation of heat as far as possible. 65 As will be understood by those familiar with the art, boilers, especially locomotive boilers, carry on the upper portions thereof steam valves of various types, known as whistle valves, and safety valves, this latter type 70 being manually or automatically operated to relieve the boiler when the steam pressure therein has reached an excessive degree. Upon operation of these valves, the escaping steam frequently contacts with the boiler 75 jacket or covering and causes rapid deterioration thereof. With this in mind, my invention relates particularly to the provision of a shield, generally in the form of a housing adapted to enclose the valve and prevent the escaping steam contacting with the boiler jacket so as to quickly destroy this protective covering. A common form of safety valve of the type commonly employed 80 upon locomotive boilers is conventionally shown at 13, this valve being usually connected by a nipple with the flanged opening 11 of the boiler, or mounted on an auxiliary steam dome formed on the boiler for this 85 purpose.

90 Referring now with particularity to the structure embodying my invention, the numeral 14 generally designates the lower section of my improved valve shield or housing, and 15 the upper complementary section. These sections are designed to be 95 removably connected and partially enclose the valve structure 13. With reference to the drawings, it will be noted that the lower housing section 14 is in the general form 100 of a cylindrical receptacle entirely open at the top and rounded at the lower edge. Formed on the bottom of this lower section 14 and depending downwardly from the center thereof is a boss 15 preferably of hexagonal formation, the purpose of which will be described more fully hereinafter. The central portion of this lower section is provided with an interior vertically extending valve supporting tube 16 of cylindrical formation, the lower end of this tube being 105 formed integrally with the bottom of the 110

section while the upper extremity terminates slightly below the upper edge of the section. In order that the section may be securely mounted in position upon a boiler and also 5 permit connection of the valve structure the lower central portion of the housing section 14 is provided with an internally screw threaded opening extending through the boss 15 which thereby provides a suitable connection flange. The upper extremity of the valve supporting tube 16 is likewise provided with an internally screw threaded opening adapted to permit connection of a valve. The lower end of the section 14 is provided 10 with a laterally extending outlet nozzle 17 provided with an internally screw threaded bore for connection with a suitable conducting pipe 18. From the foregoing description, it is apparent that this lower housing section 14 embodies a receptacle of cylindrical formation provided with means for connection on a boiler at the lower end, connection for a valve at the upper central portion and means for securing at the lower portion a conducting pipe communicating with the interior of the receptacle and arranged to conduct the exhausted steam or condensation from the housing.

Referring now to the structure of the upper complementary section 15, it will be noted that this section is in the form of a substantially semi-spherical cover, the diameter of the side walls thereof being designed to permit telescopic connection of these sections. This cover section is provided with an annular flange 19 extending laterally from the body of the cover section and disposed somewhat above the lower open end thereof. This flange is arranged so as to 30 tightly fit upon the upper edge of the lower section 14 for connection of the sections. The upper end of the cover section 15 is provided with a somewhat reduced opening 20 about which is formed a raised reinforcing ring 21. Formed on the side of this upper section and extending diametrically from the upper central opening 20 to the annular flange 19 is a raised reinforcing rib 22, the upper portion being provided with a central vertically extending slot 23, communicating with the central opening 20. This structure will permit the upper extremity of the boiler valve 13 to project slightly through the upper portion of the cover section 40 and permit the projection of the movable valve operating arm carried thereby.

It is evident, from the foregoing description and the drawings, that a separable housing structure is provided, arranged so as to 50 be conveniently mounted on a boiler so as to generally enclose the valve structure mounted thereon and designed to permit unrestricted operation of the valve when necessary. These housing sections are preferably 60 formed of cast metal, such as steel and are

designed to be durable and readily separated for disconnection of the valve.

In assembling the structure, on a locomotive or other type of boiler, the lower housing section 14 is mounted in position by the 70 connection of an externally screw threaded nipple 24, threadedly connected with the screw threaded opening formed in the lower end of the housing section and the valve opening. The boiler valve is then connected 75 with the upper end of the boiler supporting tube 16 by the use of a second nipple 25, and the valve mounted in an elevated position thereon. After these members have been securely mounted in position, the upper cover section 15 is placed in position on the lower section, the connecting portions of the sections being properly machined to permit a tight sliding connection. Thus the boiler valve will be mounted in a comparatively elevated position on the boiler and encased by the housing sections. When the boiler valve 13 is operated, a portion of the steam released thereby will escape through the upper open portion of the upper housing section, and the remainder of the steam will be condensed in the housing. The steam which does not pass upwardly to the upper end of the housing will be conducted through the pipe 18 to a suitable condenser 85 or reservoir. The escaping steam, however, will be prevented from contacting with the boiler jacket or covering 12 so as to cause rapid deterioration of the jacket about the valve connection. It is readily conceivable, 90 that this will retain the boiler covering in uniform condition and considerably reduce the cost of retaining the boiler in a properly covered condition. The utmost efficiency of the boiler will also be retained in this manner, as the destruction of the boiler covering by the escaping steam impairs the insulation effect of the covering and causes considerable loss of heat. It is therefore believed apparent, that the present invention 105 provides a structure which will be found extremely advantageous upon locomotives and similar boiler structures and thus creates substantial advancement in the art to which it appertains.

It is to be understood that the form of my invention herewith shown and described is susceptible of modification and that minor changes may be resorted to without departing from the spirit of the invention or the 110 scope of the subjoined claim.

Having thus described my invention, I claim:

A shield for steam valves comprising a lower housing section of semi-spherical formation open at its upper end and formed with a restricted opening at its lower end adapted to engage a support member, a valve supporting tube formed integral with and centrally in said lower section and pro- 125 130

vided with a screw threaded opening at its upper end to accommodate a valve, a laterally extending drain nozzle formed at the lower end of the said section, a complementary cover section of semi-cylindrical formation adapted to be telescopically fitted in the upper edge of the lower section and having an annular flange formed adjacent its lower edge resting on the upper edge of

the lower section, a steam escape opening 10 formed at the upper edge of the said cover section, and an arcuate slot formed in the side of the upper section communicating with the opening adapted to accommodate a valve operating lever. 15

In testimony whereof I affix my signature.

MAURICE SULLIVAN.
